UNITED STATES PATENT OFFICE.

FREDERICK A. THUM, OF NEWARK, NEW JERSEY.

TILTING ANODE-MOLD.

SPECIFICATION forming part of Letters Patent No. 733,095, dated July 7, 1903.

Application filed May 9, 1903. Serial No. 156,442. (No model.)

To all whom it may concern:

Be it known that I, FREDERICK A. THUM, a citizen of the German Empire, residing at Newark, in the county of Essex and State of New Jersey, have invented certain new and useful Improvements in Tilting Anode-Molds, of which the following is a specification.

My invention has reference to improvements in tilting molds for casting metallic anodes and in particular to means for facilitating the removal of the cast anodes from the molds.

For this purpose my invention consists, essentially, in hinging to the body of the mold that part of the rim which forms the end face of the upper or suspension end of the anode in such a manner that when this part of the rim is turned away from the bottom of the mold the anode is free to slide out when the mold is tilted.

Anodes with horns or arms cast thereon for the double purpose of suspension and of making electric contact are almost universally used in refining metals by electrolysis. These horns or arms, being supported upon electric conductors above the level of the electrolytes within the tanks, are not dissolved. They are a considerable addition to the resulting anode-scrap of an electrolytic refinery, and it is therefore desirable to make them as light as possible. Some difficulties have been encountered in removing such anode-castings from the molds and various means have been tried for effecting the removal more rapidly and with the least amount of labor and expense. I have overcome the difficulties by the use of a tilting mold, which has the part of the rim forming the outer edge of the upper or horn end of the anode separately hinged to the body of the mold, so that when this part of the rim is swung away from the bottom of the cavity of the mold the anode-casting can slide out longitudinally without meeting any obstruction.

My invention will best be understood when described in connection with the accompanying drawings, in which—

Figure 1 represents an elevation of a tilting mold embodying my invention. Fig. 2 is a longitudinal section on the line 1 1 of Fig. 3, showing the mold tilted after casting and the anode partly slit out. Fig. 3 is a plan

view of the mold. Fig. 4 is an end view of the mold in Fig. 3. Fig. 5 is a longitudinal section, and Fig. 6 an elevation of a modification.

Similar letters of reference designate corresponding parts throughout the several views of the drawings.

Referring now to Figs. 1, 2, 3, and 4, the letter A designates the body of the mold, which consists of a plate with trunnions *t* and with a raised rim *a*, cast thereon, following the inside of the configuration of the anode to be cast, with the exception of the horn end. This horn end of the rim is formed of a separate piece B, hinged to the body A by eye-lugs *cc*, projecting from B, eye-lugs *d d*, cast on the body A, and a hinge-bolt *e*. For casting the hinged rim B is turned flat upon the body A, so as to close the open horn end of the rim *a*.

j is a ring on the hinged rim B for turning it by the protected hand or by means of a hook. The inner face *b* of the hinged rim B is shown sloping, so that the anode thrown against it when the mold is tilted acts as a wedge and starts the rim B on its hinges.

C is the bed-plate, anchored to the foundation D by bolts *f* and provided with bearings *g* for the trunnions *t* of the mold. The bed-plate has a notch *h*, adapted to be engaged by a catch *i*, hinged to the mold, so as to hold the latter in a horizontal position for casting. The catch has an upwardly-projecting arm for releasing it by means of a hook or other suitable tool when the mold is to be tilted. Adjustable stops *k* on the sloped part of the bed-plate limit the motion of the mold when tilted for removing the anode-casting.

For casting anodes the mold is placed in a horizontal position and the rim B turned down upon the mold, as shown in Fig. 1. The metal is then poured into the cavity of the mold. After the metal has set and shrinkage has taken place the mold is tilted by releasing the catch *i*, so as to assume the position shown in Fig. 2, the throw being limited by the stops *k*. The jar will start the casting *E* to slide out, as is indicated in Fig. 2, the outer edge of the anode-casting acting as a wedge against the sloped inner face of the rim B and starting the same on its hinges. The anode-casting *E* is picked up from the position shown in Fig. 2 by a suitable track, or it may be guided by ways upon a track or run into a cooling-tank.

The mold or a series of molds may be arranged in any of the well-known ways. They may be pivoted upon stationary bed-plates or upon movable bed-plates or turn-tables, 5 the mold may be turned or tilted in any suitable manner, and the tilting of the mold, as well as the return to the horizontal position, may be effected by hand or by automatic devices, and the method of hinging the rim B, 10 so as to allow a clear passage for the anode when turned out, may be varied—for instance, as indicated in Figs. 5 and 6, where the rim B' is hinged above the body A of the mold by bolts *e* to eye-lugs *c*. The hinged arms of the 15 rim B' have holes *l*. On each side of the mold are brackets *m* with notches. A bolt *o* passes through the holes *l* in the hinge-arms of the rim B' and through the notches *n* of the brackets *m*, so as to hold the rim B' away from 20 the mold when the mold is tilted, as shown in Fig. 5 in dotted lines, but allowing it to rest freely upon the bottom of the cavity when the mold is horizontal.

My invention is not restricted to the form 25 of the anode shown. It may be applied to any form which admits the cast anode to slip out of an open end without obstruction.

What I claim as new is—

1. In a tilting anode-mold, the combination 30 with the body of the mold of a separate rim-piece hinged to an open end of the mold, which hinged rim in its normal position for casting the anode rests upon the bottom of the mold-cavity and completes the rim, and

when turned away on its hinges leaves a clear 35 passage for the anode-casting to slide out on the bottom of the mold-cavity, substantially as described.

2. In a tilting anode-mold, the combination 40 with the body of the mold of a separate rim-piece hinged to the horn end of the mold, which hinged rim in its normal position for casting rests upon the bottom of the mold-cavity and completes the rim, and when turned away on its hinges, leaves a clear 45 space for the anode-casting to slide out on the bottom of the cavity, substantially as described.

3. In a tilting anode-mold, the combination 50 with the body A of the mold of a separate rim-piece B hinged to the body A beneath the plane of the bottom of the mold-cavity, and having its edge *b* sloped to cause the anode to act as a wedge in starting the rim-piece B on its hinges, said rim-piece B in its normal position 55 for casting resting upon the bottom of the cavity of the mold, and when turned away leaving a clear passage for the anode-casting to slide out on the bottom, substantially as described.

In testimony whereof I have hereunto set my hand in the presence of two subscribing witnesses.

FREDERICK A. THUM.
